WILLIAM H. MERRICK, OF PHILADELPHIA, PENNSYLVANIA.

Letters Patent No. 76,495, dated April 7, 1868.

IMPROVEMENT IN APPARATUS FOR FILTERING SUGAR.

The Schedule referred to in these Letters Patent and making part of the same.

TO ALL WHOM IT MAY CONCERN:

Be it known that I, WILLIAM H. MERRICK, of Philadelphia, Pennsylvania, have invented an Improvement in Sugar-Filtering Apparatus; and I do hereby declare the following to be a full, clear, and exact description of the same:

My invention relates to that class of sugar-filtering apparatus in which a number of bags are suspended to a horizontal partition in a cast-iron box, the sirup passing from above the partition, and through a tube, into the bag, attached to the same, and falling, in a filtered condition, into the bottom of the box; and my invention consists in dispensing with the usual screw-tube, and using in its place a nipple adapted to an opening in the partition, so large that the bag which is attached to the nipple can be elevated through it, thereby affording facilities for readily removing and replacing the bags, an operation which, in apparatus heretofore used, demanded much exertion and tedious manipulation.

In order to enable others skilled in the art to make and use my invention, I will now proceed to describe its construction and operation, reference being had to the accompanying drawing, which forms a part of this specification, and in which—

Figure 1 represents part of a sugar-filtering apparatus, with my improvement.

Figure 2, a plan view of fig. 1.

Figure 3, a section of one of the double filtering-bags; and

Figure 4, a sectional view of part of filtering-apparatus, as heretofore constructed.

Similar letters refer to similar parts throughout the several views.

Before describing my improvements, it will be well to explain briefly the usual mode of constructing the apparatus to which my improvement relates.

A large, rectangular box, of cast iron, having openings at the side, is used, and near the upper edge of this box is a horizontal partition, part of which is represented at A, fig. 4. A number of short tubes, *a*, are screwed into this partition, each tube projecting a short distance below the same, for the reception of a nipple, *b*, fig. 4, to which the mouths of two bags, one inside the other, are secured by wrapping stout cord round them.

The inner bag, of cotton duck, is larger than the outer bag, of coarser fabric, so that the former must be corrugated or waved, as shown in fig. 3, leaving spaces or channels between the two bags, for the free passage of the sirup, after passing through the interstices of the cotton-duck, the sirup finally passing through the outer bag, and falling in a filtered state to the bottom of the box.

These bags have to be frequently removed and replaced, and this has heretofore been effected by unscrewing the nipple of each bag from the projecting tube *a*, withdrawing the bag through the side openings of the box, and, after being cleansed, reinserting it through the side openings, and screwing its nipple to the projecting end of the tube.

As there are a large number of bags in each box, and as their removal at frequent intervals is necessary, it will be evident that the operation conducted through the side openings must demand tedious manipulation, and no little exertion on the part of the operator, who must necessarily occupy an uncomfortable position during his work.

To obviate these difficulties, I secure each double bag to a nipple, *B*, of the form, or approximating to the form, shown in figs. 1 and 2, the bag being secured to the lower portion, *d*, of the nipple, while the bevelled rim *e* of the upper portion is adapted to and forms a ground joint, with the bevelled edge of an opening in the partition *A* of the box, to which the bag is thus suspended, the opening in the partition being so large that the entire bag may be elevated through it.

Different devices may be employed for seizing the nipple when the bag has to be elevated, but the plan shown in the drawing is perhaps the simplest. This consists in so far closing the top of the nipple as to leave an elongated opening, *f*, into which a L-ended instrument may be inserted, and then turned a quarter round, so as to catch beneath the projecting portions, *m*, (see red lines, fig. 1.)

It will be evident that the difficulties and inconveniences above referred to may be overcome by this mode of constructing the nipples, and adapting them to openings of such a diameter that the bags can be elevated through them.

I claim as my invention, and desire to secure by Letters Patent—

The nipple B, constructed substantially as described, for adaptation to an opening (in the partition A) large enough to admit of the passage through it of the bag attached to the nipple, all substantially as and for the purpose herein set forth.

In testimony whereof, I have signed my name to this specification in the presence of two subscribing witnesses.

W. H. MERRICK.
